DISH DRAINER

William D. Taylor, Wooster, Ohio, assignor to Rubbermaid Incorporated, Wooster, Ohio, a corporation of Ohio

Filed July 29, 1968, Ser. No. 12,950

Term of patent 14 years

Int. Cl. D7—06, 99

U.S. Cl. D44—29

FIG. 1

FIG. 2

FIG. 3

FIG. 4

FIG. 5

FIG. 6

FIG. 1 is a top plan view of a dish drainer embodying my new design.

FIG. 2 is a side elevational view thereof.

FIG. 3 is an elevational view looking toward the left end of the dish drainer as viewed in FIG. 1.

FIG. 4 is an elevational view looking toward the right end of the dish drainer as viewed in FIG. 1.

FIG. 5 is a transverse sectional view as on line 5—5 of FIG. 1.

FIG. 6 is a bottom plan view thereof.

I claim:

The ornamental design for a dish drainer, as shown.
